Primary Examiner — Ricky Pham(74) *Attorney, Agent, or Firm* — Baker & Hostetler LLP(57) **CLAIM**

I claim the ornamental design for a shaker cup mixing ball, as shown and described herein.

DESCRIPTION

FIG. 1 is a perspective view of the shaker cup mixing ball showing my new design;

FIG. 2 is a front view thereof;

FIG. 3 is a back view thereof;

FIG. 4 is a left side elevation view thereof;

FIG. 5 is a right side elevation view thereof;

FIG. 6 is a top plan view thereof; and,

FIG. 7 is a bottom plan view thereof.
